UNITED STATES PATENT OFFICE

2,656,223

ADJUSTABLE SCAFFOLD CLAMP

Percy Gray, Richmond, Calif., assignor of one-half to William Gray, Washington, D. C.

Application December 14, 1948, Serial No. 65,231

4 Claims. (Cl. 304—40)

1

This invention relates to stages or scaffolds of the type used by painters, decorators and others for providing working access to the various areas of vertical walls, ceilings, etc. These platforms must be of rugged construction to safely support one or more workmen. At the same time they must be light in weight since they are frequently shifted from one job to another. These requirements dictate the use of structural materials that provide both lightness and rigidity.

Scaffolds of the type herein referred to ordinarily comprise a pair of uprights spaced apart and joined by one or more horizontal platforms from which artisans can have unrestricted access to those portions of the vertical wall or overhead ceiling contiguous thereto. The uprights frequently take the form of a pair of step ladders or the equivalent with boards laid horizontally between the rungs thereof. Reliance is placed on the questionable rigidity of such step ladders in such arrangements since the records of mishaps involving scaffolds show that a step ladder so used is highly unstable and the frequent cause of accidents. Step ladders are so used and will probably be continued in use due to their ready availability since the nature of the work nearly always calls for a ladder in some form and since the material for the improvised platform is always at hand. In addition to planks of the dimensions of floor joists, for example, the horizontal platform is frequently made of interleaved planks so arranged as to constitute an extensible assembly that is strong but light in weight.

The use of step ladders as above described is due therefore to the fact that they are self-supporting in an erected position as well as being ordinarily on hand. Although extension ladders, particularly those in which the side rails diverge at the base are as readily available, are structurally much stronger, and are almost as often needed on the job, little attempt has been made to utilize them in staging due to the difficulty of rigidly uniting the horizontal platform and the vertical ladders. Accordingly as a matter of practice either special scaffold equipment in addition to the usual ladders carried to a job must be provided or a make-shift arrangement of step ladders and horizontal planks must be put together on the job site with consequent risk of accidents as well as obvious inflexibility and difficulty of adjustment of the component parts.

Therefore, it is an object of this invention to provide an improved scaffold clamp by means of which a pair of ordinary ladders and the usual

2

horizontal platform may be transformed into a sturdy, easily adjustable and light weight scaffold.

It is another object of the invention to provide an improved scaffold clamp which enables the weight of the horizontal platform to be carried equitably by a pair of rungs of each ladder.

It is another object of this invention to provide an improved scaffold clamp that is readily adjustable to not only different heights but also to horizontal platforms of different widths.

It is another object of the invention to provide an improved scaffold clamp that not only distributes the weight of the horizontal platform on two or more rungs of each supporting ladder but is adjustable to compensate for the variable spacing between such rungs.

It is another object of the invention to provide an improved scaffold clamp in which the horizontal platform is securely and safely locked against inadvertent dislodgement and separation of the ladder rungs therefrom when in use.

A further object of the invention is to provide an improved scaffold clamp by means of which a horizontal platform may be rigidly united to a pair of ordinary ladders of various widths to form a source and safe working scaffold.

A still further object is to provide a readily adjustable and sturdy scaffold which is largely made of components already in use by journeyman artisans and which therefore may be assembled and utilized at an extremely low cost.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Reference is now made to the drawings wherein

Figure 1 is a perspective view of one form of my improved clamp in use with a pair of ladders and horizontal platform and forming a rigid working scaffold.

Figure 2 is a plan view of the lower one of my scaffold clamps with portions of the platform and the opposite ladder omitted for the sake of clearness.

Figure 3 is an end elevation of the lower scaffold clamp of Figure 1 taken from the left end

3
of this figure and with the upper and lower portions of the ladder broken away,

Figures 4 and 5 are perspective views of the left and right portions, respectively, of a modified form of scaffold clamp,

Figure 6 is a perspective view of the safety lock employed in the clamp of Figure 4, for example, on an enlarged scale and taken from the rear of such view,

Figure 7 is a perspective view similar to Figure 6 but showing the vertical adjustment provided by my improved scaffold clamp, and Figure 8 is a vertical sectional view taken on the line 8-8 of Figure 7.

Figure 9 is a perspective view of a modified form of clamp, showing the same attached to a platform. Figure 10 is a view similar to Figure 9 but with the clamp in inoperative position and the platform removed. Figure 11 is a side view of the clamp showing the clamp of Figures 9 and 10 operatively attached to the platform and ladder.

Referring now to the first embodiment of my invention and more particularly to Figures 1 to 3 of the drawing, it will be observed that a pair of vertical ladders indicated generally by the reference numerals 1 and 2 and each of which is composed of a pair of vertically extending rails 3 and 4 separated by a plurality of horizontal rungs 5 are spaced apart by the usual distance of a horizontal stage or platform generally indicated at 6. Although ladders of the diverging base type are preferred because of their easy availability, I have shown, to emphasize the lateral stability inherent therein, diverging base extensions 7 and 8 bolted or otherwise securely attached to the lower ends of the parallelly extending vertical rails 3 and 4.

The scaffold clamp of this invention indicated generally at 9 in Figure 1 is constituted of a pair of similarly shaped members, each of which has the function of encasing the end portions of one-half of the horizontal platform 6 and distributing the weight thereof upon a pair of the adjacent horizontal and parallel rungs 5. Each such member, therefore, comprises in effect a channel formed preferably of a single piece of sheet metal bent to provide a top, triangular portion 10, an outside rectangular portion 11, a similar, bottom triangular portion 12, and an end rectangular portion 13. The inwardly extending apex portions of the upper and lower triangles of the members 9 overlap so that they may be united as by a bolt 14 and wing nut 15, the former passing through aligned apertures in the four triangles as shown in Figure 3. One pair of such triangular portions is bent upwardly as shown in Figure 3 to provide a vertically offset portion so that the major portions of the triangles lie in the same plane closely fitting the upper and lower surfaces of the planks comprising the platform. If desired, means may be provided on the end rectangular portions 13 of the oppositely disposed clamp members to enable them to be easily drawn together to insure registry of the apertures of the triangular portions referred to. Such means may comprise a pair of horizontally disposed and vertically spaced ears 13a projecting outwardly from one of the end portions 13 and a bolt 13b pivotally connected to the other end member and disposable between said ears 13a in which it may be retained and effectively shortened through rotation of a wing nut 13c threaded thereon.

Platform 6 is comprised of a series of spaced planks 16 of preferably rectangular cross section

held in spaced relation by a transverse bridge piece 17 and inter-leaved with a similar series of planks 18 united by a bridge member 19. The end portions of the planks are maintained in spaced disposed alternately thereof relation by spacer blocks 20 as is clearly shown in Figure 1. It will be understood that the two series of planks constitute an extensible assembly that may be lengthened or shortened without in any way disturbing the scaffold clamps or their connection to the ladders 1, 2 now to be described; such adjustment merely varies the extent of the central overlap of the planks.

For supporting the platform carrying portions of clamp 9 there is united to each end rectangular portion 13, a vertically extending hanger 21 formed preferably of steel strap and provided with a U-shaped hook portion 22 at its upper end adapted to fit over the upper rung nearest the platform 6 and a similarly shaped lower hook 23 adapted to partially encircle the next lower rung. To provide vertical adjustability between hook portions 22 and 23 I prefer to make the lower hook 23 of a short length of steel strap and disposed beneath the upper hook 22 in rung engaging position so that its rear flat side rests against the hanger 21. The latter is suitably apertured for receiving suitable connecting means such as bolt 24 passing also through a vertical slot in the flat side of hook 23 and permitting relative vertical adjustment between the hooks. A brace member is indicated at 25 having its ends bent over into parallelism with the bottom triangular portion 12 and the lower portion of the hanger 21, respectively, is securely united to these portions as by welding and provides thereby a strong, right triangular structure. Uniting of end rectangular portion 13 to the hanger 21 is also preferably accomplished by welding; although it will be obvious that other fastening means such as rivets could also be used.

From the foregoing it will be observed that there has been described a clamp which rigidly unites a horizontal platform or stage to a pair of spaced, vertical ladders of unusual design. Such clamp is readily detachable when it is desired to raise or lower the platform and requires merely the application of a lifting force to the clamp sufficient to enable the hook portions of the hanger to be clear of the rungs. In the event that an additional safeguard is desired to make impossible the inadvertent lifting of the hanger from the rungs, a bolt as 26 may be passed through aligned apertures in the parallel legs of the hook portions as is shown at the upper end of ladder 1 in Figure 1. This figure also shows the use of a hanger 27 having engagement with but one rather than two rungs of ladder 1 in arrangements where the scaffold rigidity is provided by the lower clamp and attached platform already described. Coupling collars 28 formed of sheet metal, for example, and encircling the abutting ends of ladder 1 and its upward extension 1a may be used to unite as many ladder sections as desired provided a sufficient number of clamps 9 are provided in the assembly as described. Also the clamp of this invention although as described is of fixed lateral extent and hence most perfectly adapted to receive a horizontal platform of the width shown in the drawing, it is nevertheless capable of accommodating platforms of lesser width by the insertion of outside spacer blocks 20 of such width as to insure a snug engagement of the platform ends within such clamp. Since the clamp extends for a con-

siderable distance in the longitudinal extent of the platform, great rigidity in the united platform ends, clamp and vertical ladders is thereby assured.

In Figures 4 to 8 of the drawing there is shown a more advanced embodiment of my invention incorporating automatic locking means for the hook portions of the hanger and the rungs and also a more easily operated adjustment for the vertically spaced hooks. Considering first the locking means referred to, attention is directed to Figures 4, 5 and 6 which show at the upper end of the hanger 21, a generally rectangular slot 30 elongated in a vertical direction and disposed opposite the hook portion 22 of the hanger 21. Pivottally mounted on the opposite face of hanger 21 is a locking dog or latch 31 having a short arm 32 which is adapted to move into and out of the slot 30. It will be noted that arm 32 is provided with an upper surface 33 which inclines downwardly when the arm is in its innermost position within the slot 30. The effect of such inclination is to more securely maintain the ladder rung in its locked position therein since an inadvertent upwardly exerted force against the platform and clamp will result in a cam-like locking movement of arm 32 in a downward direction to block to a greater extent than before the open portion of the hook 22.

The locking action of arm 32 just described is effectuated through the provision of an integral stop arm 34 diverging away from arm 32 in an outward direction serving both as a stop when in engagement with the portion of hanger 21 located just above slot 30 and also as means for moving the arm 32 outwardly when it is desired to lift the hanger hook 22 from the ladder rung 5 as when changing the elevation thereof or disassembling the scaffold.

As an integral mounting for the arms 32 and 34 I prefer to provide a vertically disposed, central arm 35 pivoted on a stub shaft 36 extending horizontally and journaled in a pair of pedestal blocks 37 and 38 which are mounted in spaced relation on the inner face of the hanger 21. Pedestal blocks 37 and 38 can be suitably welded to hanger 21. However, it is preferred to provide the angularly disposed base portions 40 thereon attached to hanger 21 as by means of screws 41 passing therethrough.

To insure that arm 32 is always in its inner position extending across the open end of the hook 22 in such manner as to lock the contained rung therein, suitable spring biasing means is provided. Such means is shown as comprising a flat spring 42 attached to hanger 21 as by a screw 43 and having an outwardly offset portion 44 extending centrally upward between the hanger 21 and the central arm 35 and pressing against the ladder to urge the arm 32 into the slot 30. It will be noted that central arm 35 is cut away from a point opposite the lower edge of slot 30 to a point below the horizontal plane containing the stub shaft 36 to provide a shoulder 45 against which the upper end of spring end 44 presses, the pedestal blocks 37 and 38 being of such horizontal height as to provide for a free movement of arm 32 into and out of slot 30.

In addition to the foregoing advantages of the automatic locking means shown in Figures 4, 5 and 6, it is desired to mention also the function of the lower curved wall of the arm 32 in facilitating passage of the rung 5 thereacross and into its seated position in the hook 22 as well as the outer curvature at 22a of the terminal hook por-

tion to allow the latter to more easily slip over the rung when moving the clamp assembly into its desired position. These features are of considerable value in the use of the invention in connection with rungs that are slightly oversize or bowed.

Figures 4, 5, 7 and 8 of the drawing also disclose an improved form of adjusting means for the hook portion of the hanger 21 whereby the lower hook 23 may be readily adjusted to compensate for the slight variation in spacing of the ladder rungs that is frequently encountered. As shown more particularly in Figures 7 and 8, instead of aperturing the hanger 21 and hook 23 for the reception of a bolt 24 as in the form of the invention first described, there is provided in the lower portion of hanger 21 a vertically elongated slot 48, rectangular in outline. Slidably confined within such slot 48 is guided a spacer block 49 which is made integral with hook 23 as by welding. Spacer block also carries on its outer face a retainer block 50 of greater width than block 49 to which it is secured as by screws 51 extending thereto. In spaced relation above the slot 48 there is provided a threaded bolt 52 extending through the hanger 21 and suitably affixed thereto and with its threaded portion extending outwardly to receive an eccentrically apertured, shouldered washer 53. The latter is formed integral with or suitably united to a wing nut 54 which is centrally apertured and threaded to engage the threaded portion of bolt 52. Accordingly as the wing nut 54 is rotated the shouldered washer 53 will also rotate and will move the retainer block 50 vertically in the slot 48 and thus vary the longitudinal relationship between hanger 21 and hook 23, consequently varying the spacing between the hooks 22 and 23. It will be appreciated that this movement is relatively slight and is sufficient only to compensate for slight irregularities in spacing of the rungs 5 which is found in many newly manufactured ladders as well as those which have been in use for some time. In practice I have found that such irregular spacing ordinarily does not exceed $\frac{1}{4}$ inch. However, for the clamp to equally distribute the weight of the platform 6 on the two adjacent rungs such adjustment is quite important since it affects the rigidity and hence the safety of the assembled unit when in use.

In Figures 9 to 11 inclusive, I have also shown the clamp of a modified construction. In this embodiment, there are provided clamping portions 56 and 57 arranged to engage respectively over and under the top and bottom surfaces of the platform at the end thereof and being connected together preferably by hinges 58 which are positioned to overlie the end face of the platform when the clamp is operatively mounted on the platform. As here shown the lower clamping portion 57 is formed with angular extensions 59 which merge with the hinge structure and are designed to abut the end face of the platform. The portions 56 and 57 are moved into tight engagement with the platform by means of a wedge 60 which depend from the upper portion 56 and is arranged to enter one of the spaces between the plank sections 16 and 18 and forcibly engage one of the spacer blocks 29 so the latter will be tightly confined between the wedge and the extensions 59. To secure the clamp in position, a bolt 61 is passed through aligned holes 62 and 63 adjacent the free ends of the clamp portions and through one of the spaces between the sections aforesaid in the platform,

the bolt 61 being retained in position by means of a wing nut 66 engaging on the threaded shank of the bolt. The hanger members 67 for mounting the clamp on the ladder are preferably welded or otherwise fixed to the extensions 59, and such hangers are each formed with the hooks 68 and 69 for engagement over the ladder rungs. A brace 71 is interposed between the lower end of the hanger members and the free end portions of the lower clamp plate 57. As will be understood, the clamp may be disengaged from the platform by merely removing bolt 61, or it may be quickly remounted on the platform by simply holding the free ends of the clamp portions apart so as to receive the end of the platform, and then replacing and tightening the bolt. If desired means may be provided for holding the plates against sidewise displacement on the end face of the platform. As here shown such means are in the form of lugs 72 projecting from the inner edge of the angular extensions 59 and arranged to seat in suitable recesses in the platform.

From the foregoing, it will be apparent that there has been described a plurality of forms of a simple, inexpensive, highly adaptable and efficient clamp which may be utilized for transforming readily available ladders and platform into a safe and strong scaffold having a wide application in many fields. It will also be understood that while it is preferable to utilize the clamps of my invention at both ends of a platform, a clamp may be utilized at only one end, and some other arrangement provided for supporting the platform at the other end.

I claim:

1. Apparatus for securing a vertical ladder and a horizontal platform into a rigid, readily adjustable scaffold unit comprising a pair of united members of oppositely facing U-configuration for receiving the end portions of the platform therebetween in firm engagement, each of said members also including an integral, vertically extending hanger having a pair of vertically spaced hook portions for seating over the adjacent rungs of said vertical ladder, one of said hook portions being provided with means for locking its supporting rung therein and the other of said hook portions including means whereby it may be relatively adjustable with respect to the other hook portion for compensating for variations in the spacing of said ladder rungs, said other of said hook portions being vertically movable relative to said hanger, and said adjustable means including a cam-like rotary element rotatably mounted on said hanger and engageable with a portion of said other hook portion for limiting vertical movement of the latter.

2. Mechanism for converting a pair of vertical ladders and a horizontal platform into a rigid, readily adjustable scaffold comprising a pair of centrally united members of oppositely facing U-configuration for receiving the end portions of the platform therebetween in secure engagement, each of said united members also including an integral, vertically extending hanger having a pair of vertically spaced hook portions for seating over the adjacent rungs of said vertical ladder, one of said hook portions being slotted, a locking arm pivotally mounted on said hanger and mov-

able into locking engagement through said slot beneath said supporting rung and outwardly from said slot into a released position, and spring means normally urging said arm into said locking engagement.

3. A device for converting a pair of vertical ladders and a horizontal platform into a rigid, readily adjustable scaffold comprising a pair of centrally united members of oppositely facing U-configuration for receiving the end portions of the platform therebetween in secure engagement, each of said united members also including an integral, vertically extending hanger having a pair of vertically spaced hook portions for seating over the adjacent rungs of said vertical ladder, one of said hook portions being vertically adjustable with respect to the other hook portion and the latter portion being slotted, a locking arm pivotally mounted on said hanger below said slot and movable into locking engagement through said slot beneath said supporting rung and outwardly from said slot into a released position, said arm including a stop member disposed outwardly of said hook portion and limiting the movement of said locking arm in one direction, and means normally urging said arm in said one direction.

4. Apparatus for converting a pair of vertical ladders and a horizontal platform into a rigid, readily adjustable scaffold comprising a pair of centrally united members of oppositely facing U-configuration for receiving the end portions of the platform therebetween in secure engagement, each of said united members also including an integral, vertically extending hanger having a pair of vertically spaced hook portions for seating over the adjacent rungs of said vertical ladder, said hanger including a longitudinally extending slot, a spacer block integral with one of said hook portions and slideable in said slot, a retainer block carried by said spacer block and a manually operated eccentrically shouldered nut carried by said hanger and rotatable to effect relative movement between one of said hook portions and said hanger whereby the spacing between said hook portions may be varied to compensate for variations in spacing of said ladder rungs.
